UNITED STATES PATENT OFFICE

ARTHUR EDWARD PINCHES, OF SHEFFIELD, ENGLAND, ASSIGNOR OF ONE-HALF TO
THE TINSLEY ROLLING MILLS COMPANY LIMITED, OF SHEFFIELD, ENGLAND

ECCENTRIC ROLLS FOR ROLLING MILLS AND THE LIKE

Application filed January 26, 1928, Serial No. 249,729, and in Great Britain January 26, 1927.

This invention relates to eccentric rolls of the type in which metal is rolled between two eccentric or shaped rolls or between one eccentric or shaped and one cylindrical roll, its 5 object being to provide means for feeding the work to the rolls at the requisite period.

The rolls are driven continuously and the gate or gap between them into which the work is fed is constantly varying in size, either in- 10 creasing or decreasing. Hitherto it has been customary to rely upon the skill of the operator to feed the work at the correct point in the revolution of the rolls, for which purpose a chalk mark or other distinguishing 15 mark is usually placed on the rolls and the work is fed when the mark attains a specified position. The result is that considerable material is wasted owing to the inability of the operator to cause the work to enter the gate 20 or gap between the rolls exactly at the required moment.

According to the present invention, however, a feed apparatus is provided and is driven synchronously with the rolls through 25 a clutch or like device which is operative to begin to drive the feed apparatus at only one definite point in a revolution of the rolls, and this point, which may be adjustable, is predetermined so that the feed apparatus 30 moves the work into the gate or gap between the rolls at precisely the desired moment when the rolls are in the proper relative position to receive the work. By such means the waste due to errors in skill and in judg- 35 ment are obviated and as it is possible greatly to increase the speed of the rolls a very much greater output is obtained from the mill.

In a convenient construction a roller capable of moving work supported thereon and hereinafter referred to as a feed roller is mounted on an axis parallel with those of the rolls and is normally stationary. It may be fitted with guide collars to grip the work, and 40 a clutch member co-axial with, and rotatable in relation to, the feed roller is driven at the same speed as the rolls, conveniently by a chain drive from one of them. A second clutch member is mounted to rotate with the feed roller and a single dog or projection is

provided on each clutch member in such manner that the dogs may either be moved into or out of an engaging position.

In order to define the position of work to be fed to the rolls a stop, which may be adjustable, is fitted so that it may be brought between the feed roller and the rolls and be withdrawn from that position. Means are provided for turning the feed roller by hand and for indicating when it is at a given po- 55 sition.

In operation the feed roller is turned into a predetermined position marked by the indicating device, the work is brought to rest on the feed roller with its end against the stop, 60 the stop is removed and the dogs on the clutch members are moved to the engaging position. When the dogs engage one another the feed roller will rotate and carry the work into the gate between the rolls which will 65 then be at the definite desired point of a revolution, determined by the adjusted position of the feed roller, to ensure the work being correctly fed. 70

In the accompanying drawing:—

Figure 1 is an elevation, Figure 2 an end view and

Figure 3 a plan of rolling mill rolls fitted with feed apparatus according to the present invention.

Like reference numerals indicate like parts throughout the drawing.

The rolls illustrated comprise a lower cylindrical roll 4 and an upper roll 5 which is eccentric to its axis of rotation or, as illustrated, is specially shaped for the rolling of a particular form in which the shape of cross section is not uniform throughout the length of the bar such as a knee-bar or brake lever bar used in the construction of railway wag- 85 on. The rolls 4 and 5 are suitably mounted and driven in housings 6 and it will be appreciated that the gate or gap between them varies in size as the rolls revolve. 90

It is therefore necessary for the work to 95 be fed at a definite point in a revolution of the rolls 4 and 5 and in carrying out the present invention a feed roller 7 is mounted between bearings 8 and 9 with its axis adjacent to, and parallel with, those of the rolls 4 and 100

5 and with its upper surface at about the level of the gate or gap between the rolls 4 and 5. The spindle 10 of the feed roller 7 is extended beyond one of the bearings 9 and is preferably supported in another bearing 11.

10 A clutch member 12 is rotatably mounted on the spindle 10 of the feed roller 7 between the bearings 9 and 11 and is continuously driven from one of the rolls 4 and 5 at the same speed as the rolls and in the same sense as the lower one 4. In the example illustrated the clutch member 12 is fitted with a toothed wheel 13 meshing with another toothed wheel 14 of the same size, the toothed wheel 14 being driven by a chain 15 from the spindle of the upper shaped roll 5. The sprockets of the chain 15 being of the same diameter the clutch member 12 will be driven at the same speed as the rolls 4 and 5 and in 20 the correct sense. The bearings of the toothed wheel 14 may conveniently be provided by extensions of the bearings 9 and 11 of the feed roller.

25 A second clutch member 16 is keyed or similarly mounted on the spindle 10 so as to slide thereon, and is caused thus to slide by means of an operating lever 17 fulcrumed at 18 and having an engagement with a groove 19 cut in the circumference of the 30 clutch member 16.

35 The two clutch members 12 and 16 have each only a single engaging dog or projection 20 and 21 respectively. Normally the feed roller 7 is stationary, the clutch member 16 being in a position, illustrated in the drawing, in which its engaging dog 21 is free of the dog 20 of the clutch member 12. As there is only a single engaging dog on each clutch member it will be understood 40 that when the sliding one 16 is moved to the operative position there is only one point in the path of the revolving dog 20 at which the sliding one 21 is engaged, and this point, which may be adjusted by turning the feed 45 roller by hand, corresponds to a definite point in the revolution of the shaped rolls 4 and 5 since the latter rotate at the same speed as the clutch member 12.

50 Any desired means may be provided for turning the feed roller by hand to adjust the point at which the dogs 20 and 21 engage. In the construction illustrated a circular ratchet 22 is keyed to or formed on the feed roller 7 and is engaged by a detent 23 operated by a hand lever 24 fulcrumed by a strap 55 embracing the feed roller 7.

60 The feed roller 7 is fitted with guide collars 26 opposite the operative portions of the rolls 4 and 5. These guide collars are intended to grip the edges of work placed between them, for which purpose their adjacent faces may be inclined and roughened as indicated in the drawing. The guide collars 26 are 65 preferably adjustable on the feed roller 7 to suit the size of work to be fed to the rolls and

to be opposite the desired gate or gap between the rolls 4 and 5 when the latter are formed with more than one operative surface. For this purpose the collars 26 may be divided and clamped on to the feed roller 70 7 as indicated in Figure 3.

75 A movable stop 27, which may be adjustable, is fitted so that it may be brought between the feed roller 7 and the rolls 4 and 5, and be withdrawn from that position. In the construction illustrated the stop 27 is carried by rollers 28 running on rails 29 fitted between the housings 6 and a handle 30 is provided for moving the stop 27 along the rails 29.

80 Means are provided for indicating when the feed roller 7 is at a given position. For this purpose a scale 31 may be marked on the feed roller adjacent to the bearing 8 and a pointer 32 be carried by the bearing to co-act with the scale 31.

85 In operation the feed roller 7 is turned into a pre-determined position, indicated by the pointer 32 and scale 31 by reciprocating the lever 24, the work is caused to be gripped by the guide collars 26 with one end against the stop 27 which is brought opposite the gate or gap between the operative portions of the rolls 4 and 5. When the work is thus adjusted the stop 27 is removed and the sliding clutch member 16 moved to the engaging position by means of the lever 17. When the dog 20 engages the dog 21 the feed roller 7 will rotate and carry the work into the gap between the rolls 4 and 5, which will then be 90 at a definite point of a revolution determined by the adjusted position of the feed roller 7.

95 The correct position for the feed roller 7 may be ascertained by dis-connecting the power from the rolls 4 and 5 and reversing the feed operation, the rolls being turned in the reverse direction and allowance being made for the thickness or extent of the dogs 100 20 and 21.

105 What I claim is:—

110 1. In a rolling mill, shaped rolls, feed apparatus and means for driving said feed apparatus synchronously with the rolls, said means including a clutch device which is adapted to be placed in operation at only one definite point in a revolution of said rolls for the purpose specified.

115 2. In a rolling mill, the combination with shaped rolls, of feed apparatus, means for driving said feed apparatus synchronously with the rolls, said means including a clutch device which is adapted to be placed in operation at only one definite point in a revolution of said rolls, and means for adjusting the point at which the clutch device becomes 120 operative for the purpose specified.

125 3. In a rolling mill, the combination with shaped rolls, of feed apparatus comprising a feed roller mounted on an axis parallel with those of the rolls, a clutch member co-axial 130

with and rotatable in relation to the feed roller at said same speed as the rolls, a second clutch member rotating with the feed roller, a single dog projection on each clutch member and means for moving the dogs into and out of an engaging position substantially as specified.

4. In a rolling mill, the combination with shaped rolls, of feed apparatus comprising a feed roller fitted with gripping guide collars and mounted on an axis parallel with those of the rolls, a clutch member co-axial with and rotatable in relation to the feed roller at the same speed as said rolls, a second clutch member rotating with the feed roller, a single dog projection on each clutch member and means for moving the dogs into and out of an engaging position, substantially as specified.

10 5. In feed apparatus for a rolling mill, the combination with shaped rolls, of a feed roller, means for driving said feed roller synchronously with the rolls, said means including a clutch device which is adapted to be placed in operation at only one definite point in a revolution of said rolls, a stop defining the position of work to be fed to the rolls and means for bringing the stop between the feed roller and the rolls and for withdrawing it.

20 6. In feed apparatus for a rolling mill, the combination with shaped rolls, of a feed roller, means for driving said feed roller synchronously with the rolls, said means including a clutch device which is adapted to be placed in operation at only one definite point in a revolution of said rolls, and means for turning the feed roller by hand and for indicating when it is at a given position.

30 7. In a rolling mill, the combination with shaped rolls, of feed apparatus comprising a feed roller fitted with gripping guide collars and mounted on an axis parallel with those of said rolls, a clutch member co-axial with and rotatable in relation to the feed roller at the same speed as the rolls, a second clutch member rotating with the feed roller, a single dog projection on each clutch member, means for moving the dogs into and out of an engaging position, a stop defining the position of work to be fed to the rolls, means for bringing the stop between the feed roller and the rolls, and for withdrawing it, and means for turning the feed roller by hand and for indicating when it is at a given position, substantially as specified.

In testimony whereof I hereunto affix my signature.

ARTHUR EDWARD PINCHES.
